UNITED STATES PATENT OFFICE.

NORMAN C. DEAN, OF UNION SPRINGS, NEW YORK, ASSIGNOR OF ONE-HALF HIS RIGHT TO SILAS S. BLISS, OF SAME PLACE.

IMPROVEMENT IN CLIP-PLATES FOR CARRIAGE-SPRINGS.

Specification forming part of Letters Patent No. 134,859, dated January 14, 1873.

To all whom it may concern:

Be it known that I, NORMAN C. DEAN, of Union Springs, in the county of Cayuga and State of New York, have invented a new and valuable Improvement in Spring-Plates; and I do hereby declare that the following is a full, clear, and exact description of the construction and operation of the same, reference being had to the annexed drawing making a part of this specification, and to the letters and figures of reference marked thereon.

Figure 1 of the drawing is a representation of a front view of my invention. Fig. 2 is a top view of my invention. Fig. 3 is a sectional view of my invention.

This invention has relation to fastenings for elliptic carriage or wagon springs; and it consists in the hereinafter-described novel construction of a metallic plate-casting, which is transversely channelled or flanged and provided with a central vertical opening, and which is secured to the under side of the axle to receive the spring-clips and prevent them from being affected by lateral strain.

In the drawing, A designates such a casting, having a hole, *a*, through the center to re-

ceive the bolt *a'*, which secures it to the axle *b* *b* designate transverse channels formed and bounded by the flanges *c* *c*. The plate A is arranged lengthwise of the axle, and is secured to it by a vertical bolt, *a'*, passing through the central hole *a*, and receives the clips which secure the spring to the axle, strengthening the same and preventing lateral displacement. The clips pass through the channels *b* under the axle, and, being embraced by the flanges *c*, are prevented from having any lateral movement whatever.

What I claim as my invention, and desire to secure by Letters Patent, is—

The metallic plate A, constructed as herein described, having the central vertical hole *a*, parallel transverse flanges *c*, and re-enforced channels *b* adapted to receive the spring-clips, substantially as and for the purpose set forth.

In testimony that I claim the above I have hereunto subscribed my name in the presence of two witnesses.

NORMAN C. DEAN.
